(57) **CLAIM**

The ornamental design for a monitor, as shown and described.

DESCRIPTION

FIG. 1 is the perspective view of a monitor showing our new design;

FIG. 2 is the front view thereof;

FIG. 3 is the rear view thereof;

FIG. 4 is the left-side view thereof;

FIG. 5 is the right-side view thereof;

FIG. 6 is the top plan view thereof;

FIG. 7 is the bottom plan view thereof;

FIG. 8 is the rear-side perspective view thereof; and,

FIG. 9 illustrates the monitor of FIG. 8 with the stand extended.

The broken lines are for illustrative purposes only and form no part of the claimed design.

References to “side”, “top”, and “bottom” in the figure descriptions are not meant to require certain in-use orientation; a monitor according to the claimed design may be used in any orientation.
